CLAIM

The ornamental design for an L-shaped workstation, as shown and described.

DESCRIPTION

FIG. 1 is a right front perspective view of an L-shaped workstation showing our new design;

FIG. 2 a right front perspective view with the hutch and desk doors open and keyboard and bottom desk shelf in extended position;

FIG. 3 is a front elevational view of the workstation of FIG. 1;

FIG. 4 is a right side elevational view thereof;

FIG. 5 is a top plan view thereof;

FIG. 6 is a rear elevational view thereof;

FIG. 7 is a left-side elevational view thereof;

FIG. 8 is a bottom plan view thereof;

FIG. 9 is a front elevational view of the workstation of FIG. 2;

FIG. 10 is a right side elevational view thereof;

FIG. 11 is a top plan view thereof;

FIG. 12 is a rear elevational view thereof;

FIG. 13 is a left-side elevational view thereof; and,

FIG. 14 is a bottom plan view thereof.
